RACK AND PAWL ACTUATED QUICK-
ACTING CLAMP

Clyde L. Gilbert, Elkhart, Ind.

Application August 17, 1945, Serial No. 610,924

5 Claims. (Cl. 144—305.)

1.

This invention relates to a hand clamp.

The chief object of this invention is to provide a quick acting, one-hand operable, positive locking C-clamp.

The chief feature of the invention resides in the simplicity of construction, positiveness of operation, and adjustability of the clamp.

The invention is characterized by a C-shaped body, provided at its mid-portion with a finger grip socket, an operating lever that locks over-center in juxtaposition to the grip, a cam operable pawl, a clamping head supporting rack rapidly movable toward and away from an anvil portion of the body and by gravity, and cam pawl movable into work locking position, together with a work engaging head, cushion supported for rack impact shock absorption, and micro-metrically adjustable relative to the rack.

Other objects and features of the invention will be set forth more fully hereinafter.

The full nature of the invention will be understood from the accompanying drawings and the following description and claims:

In the drawings,

Fig. 1 is a side elevation of an embodiment of the invention with parts in work engaging position, one combination cover and frame plate being removed for clearness;

Fig. 2 is a rear elevation of such embodiment, the actuating part being broken away and shown in section to better illustrate the cover and frame plate structure;

Fig. 3 is an enlarged central sectional view of the head end of the supporting rack, the work engaging head, and the universal, resilient and adjustable connection therebetween.

Fig. 4 is a view similar to Fig. 1 but of the rack, pawl, operating lever and immediately associated parts only and in the released, or quick action position.

Fig. 5 is a view similar to Fig. 4 with parts shown in a position intermediate between those illustrated in Figs. 1 and 4.

In the drawing 10 indicates a conventionally termed C-shaped body portion terminating at one end in the anvil portion 11. This body portion is reinforced by a central rib or fin 12 which adjacent the mid-portion of the body is enlarged as at 13 and apertured at 14 to form a finger grip or socket.

The upper end 15 of the body 10 does not extend forwardly as far as the anvil portion 11 but terminates short thereof as at 16. Extending upwardly therefrom is a base section 17 which is shouldered longitudinally as at 18.

2.

A pair of complementary combination cover and frame forming plates 19 have inwardly directed rear end flanges 20 which abut at 21. Opposite thereto are the inwardly directed front end flanges 22. The lower portions of said plates straddle the projecting portion or base 17 and all are suitably secured together by screws, rivets, or the like 23.

The rear flanges 20 are cut away as at 24 to accommodate the base 17. Base 17 extends upwardly and forwardly as at 25 and includes face 26 parallel to flanges 22 forming therewith and plates 19 a rectangular socket 27.

Slidably longitudinally in the socket 27 and along the flanges 22 is a stem 28, rectangular in transverse section and having rack teeth 29 formed in face 30 opposite the face that slides on flanges 22.

Two pins 31 and 32 extend across the plates 19 and constitute fixed bearings and may be of rivet character to secure the plates together. Slidably and pivotally mounted on pin 32 is the cam pawl 33 having the elongated slot 34 therein, which rides pin 32. The forward end terminates in the rack engaging teeth 35, of which there are three, which terminate in arcuately arranged tips. Two teeth always carry the load due to such arcuity.

The opposite end is reduced at 36 to form a projection seatable in coil spring 37 bearing on shoulder 38. This projection and a portion of the body 33 is recessed at 39 and slidably therein is stem 40 which, spaced from pawl 33, carries head 41 against which the other end of said spring 37 bears. Stem 40 extends through the spring and head 41 is curved on its rear face as at 42 to bear upon flanges 20.

The latter include the central, elongated slot 43 therein, in which rides extension 44 of the stem 40 and head 41. Spring 37, therefore, normally constrains pawl 33 toward rack engagement. Since the pawl rides stationary pin 32 through elongated slot 34, a leaf spring 45 has its forward bend end 46 bearing upwardly against the lower face of pawl 33 adjacent teeth 35 thereof. A screw 47 or the like suitably anchors the opposite end of said spring 45 to base 17, as illustrated. Hence, spring 45 normally constrains pawl 33 upwardly at its forward end or, in effect, toward clockwise rotation on pivot 32.

Pivotaly mounted on the other pivot 31 is a cam lever 48 which mounts hardened sleeve 49. This lever has a flat forward face 50 that just clears rack teeth 29 when the lever is tilted into locking and holding position. In other words,

face 50 is opposed to flanges 22 and forms therewith and plates 19 a second and elongated socket 27a in registration with socket 27 aforesaid, so that canting of said rack is prevented.

The lever, adjacent face 50, is arcuately formed as at 51, the radius of same being the distance approximately equal to that between the axis of pivot 31 and the faces of teeth 29. Lever 48 includes elongated handle 52 that initially extends rearwardly and downwardly and then extends downwardly and forwardly as at 52a to conform to the finger grip portion 13 when the lever 48 is tilted clockwise and locked over-center in holding position.

Lever 48, below pivot 31, includes two spaced and opposed faces 53 and 54 on its lower face and therebetween is intermediate cam portion 55. Extending upwardly as at 56 from the upper confronting face of the pawl 33 is the abutment providing opposite faces 57 and 58 and the centrally relieved intermediate face 59 relieved as at 60.

Fig. 1 illustrates the several parts in clamping and locked relation relative to work W. In this position the tail portion 52a is immediately contiguous to guard 13 and shoulder or face 54 of lever 48 is in engagement with shoulder or face 58 of pawl 33 and holds same forwardly while cam 55 engages face 59 of the pawl to hold the pawl against spring 45 and hence hold the rack down, so that head 60b clamps work W between it and anvil 11 for teeth 29 and 35 are engaged.

When handle 52 is elevated, see Fig. 4, shoulder or face 53 is engaged with shoulder or face 57 and the pawl 33 is retracted rearwardly against spring 37. Pin 32 limits this movement. Teeth 35 are now free of the rack teeth 29 and the rack 28 and head 60b with the interconnection therebetween may be freely slid toward and away from anvil 11. Spring 45 now holds pawl 33 elevated.

When clamping is desired, the clamp may be held in one hand with parts positioned as shown in Fig. 4 and inverted until the rack is fully retracted. The other hand then presents the work W to the clamp, the work bearing on anvil 11 and the rack 28 dropping head 60b into work engagement when the clamp is positioned as shown in Fig. 4. Then handle 52 is depressed which depresses pawl 33 against spring 45 and subject to the stop function of shoulder 53 engaged with shoulder 57, the teeth 35 loosely mesh with rack teeth 29.

Continued clockwise rotation of lever 48 by further depression of handle 52 removes pawl 33 from the aforesaid stop limitation and cam 55 now passes from depression 60 to face 59 and forces the pawl 33 counterclockwise from the position shown in Fig. 4 toward the position shown in Fig. 1. As this occurs shoulder 54 approaches shoulder 58. Final lever movement forces head 60b down on the work with the desired pressure and lever 48 locks over-center, as it were, such center being approximately that defined by a plane through the axes of pivots 31 and 32.

Actual clamping pressure is initially exerted when cam 55 starts to leave depression 60. Maximum clamping pressure is attained when cam 55 engages face 59. Thereafter lever movement is solely for locking over-center and positioning shoulder 54 immediately behind shoulder 58 to prevent accidental release of the cam lock on the rack and to retain the clamping pressure. The rack throw, by reason of cam 55 is approximately the width of two teeth.

Reference will now be had more particularly

to Figs. 1 and 3. The head 60b is slightly concaved or dished as at 60a. It includes a partially spherical socket 61 closed by collar portion 62 and therein is ball 63 having stem 64 extending from the collar. Stem 64 is carried by portion 65 that is slidable in socket 66 of member 67 having shank 68 reduced externally as at 69 and threaded as at 70. The lower end of rack 28 is apertured at 71 and threaded as at 72. By this means the shank 68 and head 60b can be advanced or retracted relative to the rack 28.

In Fig. 3 the adjustment is exhausted upwardly and available downwardly to the maximum degree. Fig. 1 shows slight downward adjustment.

For cushioning impact member 65 includes stem 73 and both are tapped and threaded as at 74. Shank 68 is recessed as at 75, same constituting a reduced extension of socket 66 and providing shoulder 76 therebetween. Shank 68 includes apertured partition 77 apertured at 78 and recessed at 79 to take head 80 of the bolt having the threaded body portion 81 threaded into tapped portion 74. A coil spring 82 envelops the bolt and sleeve extension 73 and bears at one end on face 83 of portion 65 and at its opposite end on partition 77.

When the head is dropped member 65 telescopes into socket 66 and is cushioned by spring 82. This can fully collapse into bore 75 when face 83 engages face 76 when clamping pressure is applied to the rack 28. If the rack clamping movement, following such collapse, be insufficient to properly hold the work W, the externally knurled portion 67 is rotated to adjust the head 60b relative to rack 28 so that proper pawl clamping pressure is obtained when lever handle 52 is tilted clockwise.

Having thus described the respective parts and briefly outlined the major features of operation thereof, it is now further pointed out that invention, as illustrated, by reason of the slidable extension on the toothed pawl or detent limits the clockwise rotation thereof about the axis of the pin and slot connection by reason of the lower end of the elongated slot 43 formed in the two rear flanges of the plate 19.

The lever pivot with its axis and the pawl or detent pin axis determines, as aforesaid, a plane and when the lever is sufficiently tilted clockwise it passes over center, as it were, and is self-sustaining in the over center position. When fully moved to the over center position the detent is locked, as aforesaid, against rack release and at the same time the free end of the lever is juxtaposed or closely associated with the finger grip portion 13 of the clamp body and preferably the end of that lever has slight clearance relative to the lateral projection of the lowermost portion of the body 12.

If it be assumed that the pawl or detent incident to the cam actuation forces the rack and the head toward the work for a predetermined amount of travel in the clamping direction, then the cushion spring of the cushion connection is of such character that when it is collapsed sufficiently for the two stop shoulders 76-83 to contact, the cushion travel, as it were, constitutes only about $3\frac{1}{2}$ of an inch or approximately $\frac{1}{8}$ of the pawl responsive rack travel, same being approximately $\frac{1}{4}$ of an inch, by way of example only.

It will be obvious that any desired pressure application can be imparted by the head 60b for clamping the work between the head and the anvil portion, if within the range of pressure de-

terminable by the leverage and the cam, etc. Obviously, if great pressure is desired and only limited rack travel is available only light pressure will be obtained. Consequently, the threaded adjustment connection 84—74 aforesaid between the clamping head and the rack member can be adjusted so that the desired clamping pressure will be obtained for the operative and effective travel of the rack member, the detent and the cam lever, and such adjustment for increased pressure is obtained by unthreading the threaded connection to the desired degree and a decrease in pressure is obtainable by threading operation to the desired degree.

The dished type head insures peripheral or circular contact with the work as distinguished from point or axial contact with the work. The ball and socket connection permits angular adjustment of the head to conform to any flat surface and also permits positive engagement with any other surface having a curvature of greater radius than that of the concavity in the head and permits point bearing contact, as it were, with any surface that has a curvature of greater arcuity than that of the concavity of the head.

It will be further noted that the invention herein disclosed exerts a uniform, straight and even pressure without any twisting effect, etc., upon the work. Also, the finger hole arrangement in the body of the clamp has the further feature that the clamp body spaces the fingers from the work and this is particularly advantageous when a piece of hot work is to be held by a clamp for welding or like purposes or a hot tool is to be associated with work held by the clamp. Body 10 here also serves as a shield.

The invention has the further advantage that if the smallest size clamp has its body portion provided with maximum sized finger grip and it is desired to utilize standard parts for this size, the only requisite changes will be to substitute for the body illustrated a body having a larger throat, as it were, or a smaller throat and provide a rack of greater or less length, respectively, all other parts remaining the same.

It will be further noted that the offsetting in the body portion at the end opposite the anvil end and the offsetting in the plates 19 permits the positioning of the head when fully retracted in a nested arrangement so that substantially the body full opening is available for work reception and all without enclosing the knurled adjustable member for it, in this position, is exposed at three sides and can be finger adjusted for pressure variation as previously described.

While the invention has been illustrated and described in great detail in the drawings and foregoing description, the same is to be considered as illustrative and not restrictive in character.

The invention claimed is:

1. In a clamp structure having an anvil and a work clamping head movable toward and away from same, the combination of a reciprocable rack toothed member supporting the head, a lever pivotally mounted in spaced relation to the member, a multiple-toothed member movable toward and away from the rack toothed member for tooth engagement and disengagement, lever operable cam means for moving the second mentioned toothed member toward the anvil for effecting rack member and head movement toward the anvil for work clamping purpose, said lever operable cam means and said multiple-toothed member each having a pair of spaced op-

- posed shoulders, the spacing of one pair being different from that of the other pair of shoulders, and means normally constraining said multiple-toothed member toward rack engagement, lever operation retracting the multiple-toothed member in opposition to the constraining means, at least two teeth of the multiple-toothed member having engagement with the rack toothed member when the latter exerts pressure upon the head.
2. In a clamp structure having an anvil and a work clamping head movable toward and away from same, the combination of a reciprocable rack toothed member supporting the head, a lever pivotally mounted in spaced relation to the member, a multiple-toothed member movable toward and away from the rack toothed member for tooth engagement and disengagement, lever operable cam means for moving the second mentioned toothed member toward the anvil for effecting rack member and head movement toward the anvil for work clamping purpose, mounting means of a pin and elongated slot type for the multiple-toothed member, the slot of said means being directed generally longitudinally with respect to the multiple-toothed member, and yielding means normally constraining the multiple-toothed member away from the anvil, and in opposition to the cam means operation thereof.
3. A clamp structure as defined by claim 2 wherein the multiple-toothed member has pivotal movement about the pin axis of said mounting means, a tail slidable longitudinally with respect to the multiple-toothed member, guide mechanism of pin and elongated slot type and associated with that tail, and yielding means interposed between the multiple toothed member and the guide mechanism constraining that member and tail toward extended position.
4. In a hand clamp having a clamping head supporting rack, and a multiple-toothed member movable toward and away from same for engagement and disengagement therewith, the combination of a cam provided lever pivotally mounted in juxtaposition to said member and having a cam portion arranged upon lever actuation to engage and move said member, rack and head into the clamping direction, and shoulder means on the lever and member adjacent the cam engaged portion of the member for predetermined engagement upon predetermined positioning of the lever, the lever, when the shoulder means is engaged, having a self-sustaining over-center position, the shoulder means on the lever and the member being disposed at opposite sides of the cam portion and cam engaged portion and each comprises opposed shoulders, one adjacent pair of shoulders when engaged and the lever is sufficiently tilted in one direction effecting retraction of the member from rack engagement, and the other adjacent pair of shoulders when the lever is sufficiently tilted in the opposite direction preventing accidental disengagement of the member from the rack.
5. In a clamp having an anvil, an opposed head and a member for moving the latter toward and away from the anvil for clamping and release purpose, the combination of a connection between the member and head comprising an intermediate member, complementary ball and socket means between the head and the intermediate member, a second intermediate member between first mentioned member and the first mentioned intermediate member, adjustable yielding means between the intermediate members which are

longitudinally slidable relative to each other for cushion purposes, and means adjustably connecting the first mentioned member and second mentioned intermediate member together.
